CLAIM

The ornamental design for a dish washer, as shown and described.

DESCRIPTION

FIG. 1 is a front, right perspective of the front panel for the dish washer showing my new design;

FIG. 2 is a front view thereof;

FIG. 3 is a rear view thereof;

FIG. 4 is a left side view thereof, the right side view being a mirror image thereof;

FIG. 5 is a top plan view thereof; and,

FIG. 6 is a bottom plan view thereof.

The broken line showing of interior details in FIG. 5 is included for the purpose of showing environmental portions of the dish washer and forms no part of the claimed design.
